UNITED STATES PATENT OFFICE.

WILLIAM SCOTT, OF LOCHEE, DUNDEE, SCOTLAND.

SACK-FEEDER.

1,385,930.

Specification of Letters Patent.

Patented July 26, 1921.

Application filed March 2, 1918. Serial No. 220,055.

(GRANTED UNDER THE PROVISIONS OF THE ACT OF MARCH 3, 1921, 41 STAT. L., 1313.)

To all whom it may concern:

Be it known that I, WILLIAM SCOTT, a subject of the King of Great Britain and Ireland, and a resident of Lochee, Dundee, Scotland, have invented certain new and useful Sack-Feeders, for which I have made application in England, dated Jan. 16, 1917, Patent No. 110,077, of which the following is the specification.

10 This invention relates to feed mechanism for rotary sack-printing and like machines, of the type in which the material to be treated is fed by a single endless horizontally traveling cloth; and has for its object to improve the construction of such feeding mechanism so that two or more attendants may be able to feed the machine in series at the same time and thus increase the output of the machine, while lessening the labor of each

20 attendant.

The improved feed mechanism comprises essentially a usual endless horizontally traveling feed cloth, a plurality of tables arranged in series on which is placed the material to be transferred by the attendants to the feed cloth, one or more of the tables extending over a part or parts of the feed cloth and the last table being to the rear thereof, and timing rollers for each attendant so that the material fed to the cloth travels forward at the proper time.

An illustrative example of the improved feed mechanism as applied in connection with a rotary printing cylinder is shown on three accompanying sheets of explanatory drawings, Figure 1, Sheet 1, being a plan, Fig. 2, Sheet 2, a side elevation, and Fig. 3, Sheet 3, an end elevation thereof.

As shown in the drawings there works in conjunction with a rotary printing cylinder A an endless traveling feed cloth B supported by rollers C, D, E, one E of these rollers being driven in usual manner by gearing (not shown) from the shaft of the printing cylinder. To enable two attendants to feed the machine at the same time, two tables G, H are provided on each of which is placed a pile J of sacks or the like to be fed on to the traveling feed cloth B. One H of these tables is so made and placed, as shown, that its top extends over a part of the feed cloth B, one of the attendants feeding on to the cloth from the end of this table H next to the printing cylinder A. The other attendant

55 feeds the sacks from the pile J on the other table G on to the part of the upper surface of the feed cloth which is beneath the inclined rear part of the top of the forward table H. If preferred the two tables G, H may be in one structure with a feeding gap 60 where the feed cloth passes over the roller C.

Where the forward attendant places the end of the sacks on his table H on to the feed cloth B there are the usual timing rollers K, L carried and actuated as shown from a cam 65 M on a transverse shaft driven through gearing N from the shaft of the printing cylinder A; and similar timing rollers P, Q are also placed where the second attendant places the end of the sacks taken from the 70 pile on the other table G on to the feed cloth. These timing rollers P, Q are carried by a spindle supported in levers R, S journaled in the sides of the table H and connected by a stirrup T with one end of a cord or chain U 75 passing over guide pulleys V, W to the upper end of a lever X journaled in the framing of the machine, this lever being so shaped that a roller Y on it also bears on the timing cam M. This cam so acts through the gearing described on the two sets of timing rollers K, L and P, Q that the sacks are fed onto the cloth B successively and travel forward one after the other to the printing cylinder without interfering one with the 85 other.

For triple feeding there will be two tables the tops of which are above the traveling feed cloth and a third table to the rear thereof with the necessary timing rollers 90 for all three attendants, the traveling cloth being lengthened and the machine speeded up accordingly.

I am aware that in feed mechanism applicable to certain rotary sheet printing machines and sheet folding machines it has hitherto been proposed to provide a number of feeding tables and timing appliances regulating the delivery of the sheets; but in such machines there have either been a 95 plurality of feed ways, or the feed mechanism has consisted of cloths, webs, or tapes with or without grippers and traveling in other than a horizontal plane only.

In the claims the word "Number" is to be 105 understood to include one or more.

What I claim is:—

1. In rotary sack-printing and like ma-

chines of the type described; feed mechanism comprising in combination an endless feed cloth traveling only in a horizontal plane, a plurality of tables arranged in series on which is placed the material to be transferred to the feed cloth, certain of these tables extending over the feed cloth and the last table being to the rear thereof, and timing rollers for each attendant so that the material fed to the cloth travels forward at the proper time, as described.

2. In rotary sack-printing and like machines of the type described; feed mechanism comprising in combination an endless feed cloth traveling only in a horizontal plane, a plurality of tables arranged in series on which is placed the material to be transferred to the feed cloth, one table extending over a part of the feed cloth, a second table to the rear thereof, and timing rollers for each attendant so that the material fed to the cloth travels forward at the proper time, as described.

3. In rotary sack-printing and like ma-

chines of the type described; feed mechanism comprising in combination an endless horizontally traveling feed cloth, a plurality of tables arranged in series on which is placed the material to be transferred to the feed cloth, certain of these tables extending over the feed cloth and the last table being to the rear thereof, usual timing rollers for the forward attendant, timing rollers for the rear attendants, levers supporting these latter rollers, a stirrup connecting the levers, a further lever journaled at the forward end of the machine, a flexible connection between this forward lever and the stirrup, a roller on the forward lever and a timing cam on which the roller bears, as described.

In testimony whereof I have signed my name to this specification, in the presence of two subscribing witnesses.

WILLIAM SCOTT.

Witnesses:

WILLIAM ELDER,
WILLIAM KENNEDY.
